CLAIM

The ornamental design for a license plate frame, as shown and described.

DESCRIPTION

FIG. 1 is a front-left isometric view of a first embodiment of a license plate frame in accordance with the present invention.

FIG. 2 is a front view of the license plate frame of FIG. 1.

FIG. 3 is a bottom view, wherein the top view is a mirror image, of the license plate frame of FIG. 1.

FIG. 4 is a right-side view, wherein the left side view is a mirror image, of the license plate frame of FIG. 1.

FIG. 5 is a front-left isometric view of a second embodiment of a license plate frame in accordance with the present invention.

FIG. 6 is a front view of the license plate frame of FIG. 5.

FIG. 7 is a bottom view, wherein the top view is a mirror image, of the license plate frame of FIG. 5.

FIG. 8 is a right-side view, wherein the left side view is a mirror image, of the license plate frame of FIG. 5.

FIG. 9 is a front-left isometric view of a third embodiment of a license plate frame in accordance with the present invention.

FIG. 10 is a front view of the license plate frame of FIG. 9.

FIG. 11 is a bottom view, wherein the top view is a mirror image, of the license plate frame of FIG. 9; and,

FIG. 12 is a right-side view, wherein the left side view is a mirror image, of the license plate frame of FIG. 9.
